(57) **CLAIM**

The ornamental design for a game controller, as shown and described.

DESCRIPTION

FIG. 1 is a perspective view of a game controller, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures illustrate portions of the game controller that form no part of the claimed design.

The broken lines on the directional buttons of FIGS. 1 and 6 are included to show unclaimed edges on the article.

The broken lines on the top of the joysticks of FIGS. 1 and 6 are included to show unclaimed edges on the articles.

The broken lines around the bases of joysticks of FIGS. 1 to 6 are included to show unclaimed ring protrusions on the articles.

1 Claim, 4 Drawing Sheets
